UNITED STATES PATENT OFFICE

149,035

DESIGN FOR A TEXTILE FABRIC OR SIMILAR ARTICLE

Joseph P. Arcuni, Long Island, N. Y.

Application June 9, 1947, Serial No. 139,554

Term of patent 3½ years

(Cl. D92—1)

To all whom it may concern:

Be it known that I, Joseph P. Arcuni, a citizen of the United States, residing at Long Island, county of Nassau, State of New York, have invented a new, original, and ornamental Design for a Textile Fabric or Similar Article, of which the following is a specification, reference being had to the accompanying drawing, forming part thereof, wherein the figure is a plan view of a textile fabric or similar article, showing my new design.

A design unit is outlined by dot and dash lines. Said unit is repeated in a drop repeat as indicated.

I claim:

The ornamental design for a textile fabric or similar article, substantially as shown.

JOSEPH P. ARCUNI.
